C. C. SUNDERLAND.
ROPE THIMBLE,
APPLICATION FILED NOV. 10, 1916.

1,244,658.

Patented Oct. 30, 1917.

INVENTOR:

Charles C. Sunderland
by his Atty.
Philip George Reed Kennedy

UNITED STATES PATENT OFFICE.

CHARLES C. SUNDERLAND, OF TRENTON, NEW JERSEY, ASSIGNOR TO JOHN A. ROEBLING'S SONS COMPANY, A CORPORATION OF NEW JERSEY.

ROPE-THIMBLE.

1,244,658.

Specification of Letters Patent. Patented Oct. 30, 1917.

Application filed November 10, 1916. Serial No. 130,567.

To all whom it may concern:

Be it known that I, CHARLES C. SUNDERLAND, a citizen of the United States, residing at Trenton, county of Mercer, and 5 State of New Jersey, have invented certain new and useful Improvements in Rope-Thimbles, fully described and represented in the following specification and the accompanying drawings, forming a part of the 10 same.

This invention relates to an improved thimble for use with wire ropes, the object being to provide a strong and simple thimble which is readily connected to or disconnected from hook eyes or similar closed connections. The thimble is intended especially for use in wire rope slings, where it enables a drop forged hook to be used with 15 integral closed eye, thus avoiding the necessity for a separate ring to connect the thimble to the hook eye, but the invention is of general application with rope thimbles.

In the accompanying drawing, forming a part of this specification, there is shown 25 a rope thimble embodying all the features of the invention in their preferred form as applied to wire rope slings and the like, and this construction will now be described in detail, and the features forming the invention 30 then specifically pointed out in the claims.

In the drawing—

Figure 1 is a side view of the rope eye, with the thimble in place, and shown partly 35 in section;

Figs. 2, 3 and 4 are sections on, respectively, the lines 2—2, 3—3, and 4—4 of Fig. 1.

Referring to the drawings, the thimble or 40 eye piece is formed of two sections A, A' divided longitudinally of the thimble and secured together by rivets, bolts or like securing means 10 through the bodies of the two sections, so as to form the usual groove for 45 receiving the rope X. The section A is open at its outer end as at 2, and section A' is open at the inner end as at 3. These openings are filled by tongues formed integrally with the sections, the tongues being of such 50 size as to fit snugly within the openings and completely fill the same, the tongue 4 of section A entering and closing the open end 3 of section A', and the tongue 5 of section A' entering and closing the open end 2 of section A. The two parts of the thimble are

preferably provided at their inner end with studs 12, 13 outside the rope groove, these studs extending in opposite directions from the parts A, A', and overlapping so as to form a ring by which the rope is held in 60 place. These studs preferably are wedge-shaped for tightness, as shown, and are preferably secured together for strengthening the thimble, being shown as provided with holes through which pass pins 11 secured by rivets 1 to hold the studs and thimble parts together.

In addition to the overlapping studs, 12, 13, for holding the two parts of the thimble from shifting on each other under rope tension, the two parts A, A' preferably are provided with corresponding recesses and studs 14, 15 on opposite sides of the thimble, so that the shoulders on these engaging studs and recesses aid in strengthening the thimble against the rope tension. The thimble may be used without any means at the outer end of the thimble for holding the rope in the thimble groove, but preferably the two parts of the thimble A, A' are provided with overlapping ears 16 for holding the rope in place, as usual in other thimbles. The thimble shown is especially adapted for wire rope slings or other uses where the equalization of tension on the two parts of the rope 75 loop is important, and for this purpose the thimble is such that the rope is free to slide on the thimble under strain while of great 80 strength and resistance to change of form.

The hook eye or other similar member is 85 readily applied to the thimble by passing the eye through the open end of one of the thimble sections, then through the open end of the other thimble section, and then securing the sections together. The provision 90 of the tongues entering and closing the open ends has greatly strengthened the thimble and provided for strengthening of those 95 parts most liable to wear and breakage.

It is not intended that the invention shall 100 be limited to the specific form shown in the drawings, as detail changes may be made without departing from the invention as defined by the claims.

What is claimed is:

1. A rope thimble consisting of two parts, the line of division being longitudinally of the thimble, and the parts being open at opposite ends.
2. A rope thimble consisting of two parts,

the line of division being longitudinally of the thimble, each part being open at one end and having a tongue portion at the other end, the tongue on one part being adapted to enter and close the open end of the other part.

3. A rope thimble consisting of two parts, the line of division being longitudinally through the rope groove, each part being 10 open at one end and having a tongue at the opposite end, the open end and the tongue of the one part being at opposite ends to the open end and tongue of the other part, the tongues being adapted to enter and close the 15 open ends, overlapping studs on the two parts acting to hold the two parts against slip on each other, and means for securing the two parts together to form a thimble.
4. A rope thimble consisting of two parts 20 A, A', the line of division being longitudinally through the rope groove, each part

having respectively open ends 2 and 3, tongue portions 4 and 5, overlapping studs 12, and 13 at the inner end of the thimble outside the grooves having openings in line, 25 and locking pin 11 passing through said openings.

5. A rope thimble consisting of two parts A, A', the line of division being longitudinally through the rope groove, each part 30 having respectively open ends 2 and 3, tongue portions 4 and 5, overlapping studs 12, and 13 at the inner end of the thimble outside the grooves having openings in line, locking pin 11 passing through said openings, and corresponding recesses and studs 25 14 and 15 on the two parts of the thimble between its ends.

In testimony whereof, I have hereunto set my hand.

CHARLES C. SUNDERLAND.
